UNITED STATES PATENT OFFICE

160,817

FISHING REEL

Henry G. Shakespeare and Gerald D. Harrington,
Kalamazoo, Mich., assignors to Shakespeare
Company, Kalamazoo, Mich.

Application December 14, 1949, Serial No. 6,598

Term of patent 14 years

(Cl. D31—4)

To all whom it may concern:

Be it known that we, Henry G. Shakespeare and Gerald D. Harrington, citizens of the United States, residing at Kalamazoo, county of Kalamazoo, and State of Michigan, have invented a new, original, and ornamental Design for a Fishing Reel, of which the following is a specification, reference being had to the accompanying drawing, forming a part hereof.

Fig. 1 is a side elevational view.

Fig. 2 is a bottom view.

Fig. 3 is a rear end elevational view of a fishing reel embodying our new design.

We claim:

The ornamental design for a fishing reel, as shown.

HENRY G. SHAKESPEARE.
GERALD D. HARRINGTON.
